UNITED STATES PATENT OFFICE.

LEE R. SCARBOROUGH, OF SEMINARY HILL, TEXAS, ASSIGNOR TO LLOYD C. KELLY,
OF PINEVILLE, KENTUCKY.

DESIGN FOR A BADGE, BUTTON, PIN, BROOCH, OR EMBLEM.

58,945.

Specification for Design.

Patented Sept. 6, 1921.

Application filed August 21, 1920. Serial No. 405,206. Term of patent 7 years.

To all whom it may concern:

Be it known that I, LEE R. SCARBOROUGH, a citizen of the United States, residing at Seminary Hill, in the county of Tarrant and State of Texas, have invented a new, original, and ornamental Design for Badges, Buttons, Pins, Brooches, or Emblems, of which the following is a specification, refer-

ence being had to the accompanying drawing, forming part thereof.

The figure is a plan view of a badge or emblem, showing my new design.

I claim:

The ornamental design for a badge, button, pin, brooch, or emblem, as shown.

LEE R. SCARBOROUGH.
